UNITED STATES PATENT OFFICE.

MAURICE ANDERSON, OF CHICAGO, ILLINOIS.

PNEUMATIC-TUBE CARRIER.

Application filed December 15, 1926. Serial No. 155,052.

This invention relates to a carrier for pneumatic tubes and has for its object to provide a new and improved device of this description. The invention has as a further 5 object to provide a carrier with an indicating device which will not be displaced or disarranged while the carrier is being transferred from one point to another. The invention has as a further object to provide 10 a carrier which can be passed through the tube with either end to the front without sticking in the tube. The invention has further objects which are more particularly pointed out in the accompanying description.

15 Referring now to the drawings:

Figure 1 is a view showing one form of the carrier embodying the invention.

Figure 2 is a view of one end of the carrier shown in Figure 1 with the indicating 20 device in the process of being moved to change the indication.

Figure 3 is a view showing the inner member of the indicating device.

Figure 4 is an enlarged sectional view 25 taken on line 4—4 of Figure 1 with parts omitted.

Figure 5 is a sectional view taken on line 5—5 of Figure 4.

Figure 6 is an end view of the carrier 30 shown in Figure 1.

Figure 7 is an enlarged sectional view through the indicating device with parts omitted.

Figure 8 is an enlarged view of a portion 35 of one of the rings of the indicating device showing the notches for the springs.

Figure 9 is a view showing modifications in construction.

40 Like numerals refer to like parts throughout the several figures.

In the drawings I have shown a carrier having a hollow central section 1. The device is provided with a removable inclosing section 2. This inclosing section is provided 45 with the end piece 3 which is preferably of some material such as felt and which acts as a piston so that the air may force the carrier through the tube. The enclosing section 2 slides off and onto the end of the section 1. In certain uses of carriers of this kind, a carrier is sent from one department to another and it is necessary to indicate either the department from which the carrier came or the department to 50 which it is to be sent. Some suitable indicating device for this purpose must be used.

In the construction shown, the inclosing section 2 is provided with an indicating device which in Figures 1 to 4 inclusive is shown as consisting of a sleeve 4 which forms part of the inclosing section and which is provided with indicating means or devices such as figures 0 to 9 as illustrated in Figure 3.

In order to give a greater range of indications, a second series of indicating devices or figures 0 to 9 is placed upon a ring 5 which surrounds the sleeve 4, the two sets of indicating devices or figures adapted to cooperate. A second ring 6 is placed around the sleeve 4 so as to conceal the indicating devices or figures thereon and is provided with an opening 7 through which one of such figures may be disclosed. The rings 5 and 6 are rotatively mounted upon the 70 sleeves 4 and are also free to be moved rotatively therealong.

The sleeve 4 is provided with an inclosing end piece 8. The ring 6 is provided with a series of notches 9 at suitable intervals and one or more springs 10 are attached to the end piece 8. The ends of these springs engage the end of ring 6 and the springs are so attached as to permit their ends to move outwardly when pressure is applied to said 80 ends. The notches 9 in the ring 6 are arranged so that when the ring is rotated, the springs will be pressed out and will slide along the edge of the ring and will then drop into the next notch. One of these 90 notches is shown enlarged in Figure 8. Both rings 5 and 6 are movable longitudinally along the sleeve 4. The ring 5 is provided with a series of notches 10 (Figure 2,) and the sleeve 4 is provided with a projection 11 adapted to fit into these notches. When it 95 is desired to adjust the indicating device the rings 5 and 6 are moved longitudinally along the sleeve 4 in a direction away from the projection 11 and until said projection is released from its associated notch. The ring 5 may then be moved in either direction, the projection 11 sliding along the edge of the ring.

When any desired figure or indication on 105 the ring is not in the desired position, the ring is released and the projection 11 enters on the slots 10^a and holds the ring against accidental movement. When it is desired to change the indicating devices indicated by the ring 6, said ring is rotated in either direction and this rotation causes 110

the springs to be moved out of the notches 9 and slide along the edge of the ring. When the desired figure to be indicated by the ring 6 is reached, the springs will enter 5 the associated notch 9 and hold the ring against accidental movement. If the indication desired to be made is, for example, Figure 1, the ring 6 will be moved until the opening 7 comes opposite the zero mark on 10 the sleeve 4 as indicated in Figure 1. Any other indications up to 9 will be made by moving the ring 5 until the desired indication is opposite the zero showing through ring 6. This movement of the ring 5 as 15 before stated, is brought about by moving both rings 5 and 6 along the sleeve 4 toward the springs 10 until the pin 11 is released and then rotating ring 5 until the desired position is reached, whereupon the springs 10 20 will move the rings along the sleeve 4 so as to cause the pin 11 to enter its associated notch 10. The sleeve 4 is provided with a stop 12 which limits the movement of the rings 5 and 6.

25 When it is desired to give an indication greater than 9, the ring 6 is moved or, if necessary, both rings 5 and 6 are moved until figure 1 is exposed through the opening 7 and the figure 0 on ring 5 is opposite thereto. A further increase in the indicating movements is produced by moving ring 5 through its cycle until the figures 1, 2, 3, etc., thereon come opposite the figure 1 exposed through opening 7. A further increase in indicating numbers is then produced by moving ring 6 to a different number and repeating the process above set out. The notches in ring 6 for the springs 10 are 30 arranged so that when the springs are in said notches, the opening 7 is opposite one of the indications on sleeve 4. The notches 10 in ring 5 are so arranged that when the projection 11 is in one of those notches, the figures on ring 5 are opposite the figures on 35 sleeve 4. It will therefore be seen that the indicating device is so arranged that it cannot be accidentally displaced.

At the other end of the section 1, I provide a door 14, by means of which access is 40 secured to the carrier. The door is provided with any suitable hinge. In the construction shown, there is a flexible piece 15 which extends around the end of the carrier, and which is preferably of leather. This 45 piece is provided with a projecting part 16 which extends over the door and is fastened thereto by the fastening device 17, and acts as a hinge for the door.

There is also a fastening member 18, which 60 is shown as a part of the flexible member 15, and which is provided with a catch 19 which extends over a fastening piece 20 so that when the catch is attached to the fastening piece, the door is locked in position 65 so that it cannot be accidentally opened.

This door is provided with an engaging part 21 which engages the inner face of the tube, and which is, preferably, of felt so as to act to prevent the escape of air past the carrier in the event it is placed in the tube with the 70 wrong end first.

The engaging piece 21 is cut away for the hinge 16 and the fastening piece 18 as clearly shown in Figure 6.

In Figure 9 I have shown a carrier with 75 only one set of indicating devices—one of these indicating devices 7 showing through the opening 7^a in the ring 6^a. This device is like that shown in Figure 2 except that the ring 5 is omitted. The parts 3 and 21 act 80 as pistons when the carrier is in the tube and hence either end of the carrier may be the forward end. The edge of the door is cut away for the pieces 18 and 16 so as not to interfere with the piston action. The springs 85 10 are locating members as they locate and hold the ring 6 in any of its positions where an indicating device will be exposed through the hole 7. They also act to return the rings 90 5 and 6 to their initial position after they are moved laterally or along the sleeve 4 in adjusting the ring 5.

One means is preferably provided for protecting the indicating device. In the construction shown, the end piece 3 is made of 95 some shock absorbing material, such as felt and projects beyond the indicating device so that when the periphery of the end piece 3 engages the wall of the tube, the indicating device will be free from such surface. 100

Back of the end piece 3 is a flexible piece 3^a. An enclosing, protecting member 3^b encloses the springs 10 and is provided with an annulus 3^c which extends over the end of the indicating device as shown in Figure 105 4. When the carrier is in the tube, the end piece 3 engages the tube and the indicating device is out of contact therewith. When the carrier is out of the tube, the end piece 3 engages any surface against which the carrier may be thrown so as to prevent the indicating device from receiving the blow. 110

It will be seen that by means of this construction, the indicating device is protected so that it cannot be accidentally injured. 115

I claim:

1. A carrier for pneumatic tubes comprising a hollow section, a removable enclosing section at one end thereof comprising a sleeve slidably mounted on said section, a series of indicating characters on said sleeve, a ring rotatably mounted on said sleeve and provided with an opening through which said characters may be made to successively appear, a plurality of notches in the edge of said ring and an automatic, locating member adapted to be automatically moved out of and into said notches responsive to rotary movement of said ring. 125

2. A carrier for pneumatic tubes comprising 130

ing a hollow section, a removable enclosing section at one end thereof comprising a sleeve slidably mounted on said section, a series of indicating characters on said sleeve, 5 a ring rotatably mounted on said sleeve and provided with an opening through which said characters may be made to successively appear, a plurality of notches in the edge of said ring, an automatic, locating member 10 adapted to be automatically moved out of and into said notches responsive to rotary movement of said ring, a second ring rotatably mounted on said sleeve and having a series of indicating characters thereon and means for holding said ring against displacement when one of the characters thereon is opposite the character exposed through the hole of the other ring.

3. A carrier for pneumatic tubes comprising a hollow section, a removable enclosing section at one end thereof comprising a sleeve slidably mounted on said section, a series of indicating characters on said sleeve, a ring rotatably mounted on said sleeve and provided with an opening through which said characters may be made to successively appear, a plurality of notches in the edge of said ring, an automatic locating member 25 adapted to be automatically moved out of and into said notches responsive to rotary movement of said ring, a second ring rotatably mounted on said sleeve, a series of notches on the edge of said second ring, a projection adapted to project into one of said notches when an indicating device on the second ring is opposite the indicating device exposed through the opening in the first ring.

4. A carrier for pneumatic tubes comprising a hollow section, a removable enclosing section at one end thereof comprising a sleeve slidably mounted on said section, a series of indicating characters on said sleeve, a ring rotatably mounted on said sleeve and provided with an opening through which said characters may be made to successively appear, a plurality of notches in the edge of said ring, a movable locating member 45 adapted to be automatically moved out of and into said notches when the ring is rotated, a second ring rotatably mounted on said sleeve, a series of notches on the edge of said second ring, a projection adapted to project into one of said notches when an in-

dicating device on the second ring is opposite the indicating device exposed through the 55 opening in the first ring, both of said rings adapted to be moved longitudinally along said sleeve so as to release said projection from its associated notch in said second ring.

5. A carrier for pneumatic tubes comprising a hollow section, a removable enclosing section at one end thereof comprising a sleeve, two indicating rings rotatably mounted on said sleeve and adapted to be moved 60 longitudinally therealong, an elastic locating member engaging one of said rings and adapted to prevent it from being accidentally displaced, said locating member acting to move said rings back to their initial position 65 after they are moved longitudinally along said sleeve.

6. A carrier for pneumatic tubes comprising a hollow section, a piston end piece connected with one end of said section, a door 75 at the other end of said section, a flexible piece extending around the end of said section near said door, said flexible piece provided with a flexible projection which is adapted to said door and acts as a hinge, 80 the door being cut away at the edge at the point where the flexible projection passes it.

7. A carrier for pneumatic tubes comprising a hollow section, a piston end piece connected with one end of said section, a door 85 at the other end of said section, a flexible piece extending around the end of said section near said door, said flexible piece provided with a flexible projection which is adapted to said door and acts as a hinge, 90 the door being cut away at the edge at the point where the flexible projection passes it, said door provided with a periphery which acts as a piston.

8. A carrier for pneumatic tubes comprising a hollow section, an indicating device at one end of said hollow section comprising a rotatable ring, a non-locking locating device engaging the edge of said ring which holds the ring against accidental displacement but 95 permits it to be rotated by the user.

Signed at Chicago, county of Cook and State of Illinois, this twenty-fourth day of November, 1926.

MAURICE ANDERSON.
